UNITED STATES PATENT OFFICE

2,185,471

POWER HAMMER

Arthur William Mall, Chicago, Ill.

Application June 15, 1937, Serial No. 148,361

13 Claims. (Cl. 125—33)

My invention relates to improvements in power hammers and similar mechanisms.

My invention relates more particularly to a power hammer or similar mechanism adapted to be driven by means of a flexible shaft drive.

Power hammers of the type to which I refer have in the past been driven by means of electric motors or by compressed air and are principally used for impacting purposes such as chipping, 10 drilling, riveting or tamping broken stone or similar ballast by means of a chisel, drill, rivet set, tamper bar or the like, to one end of which the striking member such as the hammer, piston, or power hammer imparts its blow.

15 The principal object of the present invention is to provide an improved mechanical power hammer or similar unit capable of being driven by a flexible drive shaft from a remotely positioned source of power.

20 A further object of the present invention is to provide in a power hammer of the type described a roller cam means for operating the piston back against the top of the cylinder head to compress the same, whereby the hammer blow is caused by the force of the piston instead of 25 the direct drive to the cam.

A further object of the present invention is 30 to provide an improved construction of power hammer whereby the cylindrical housing and associated parts are capable of independent removal for repair or renewal.

35 A further object of the present invention is to provide in connection with the reciprocating piston improved cushioning means for the bottom of the piston stroke.

40 A further object of the invention is to provide in connection with the reciprocating lever driven by the roller cam and adjustable shock absorber means capable of yieldingly permitting the lever to be carried downwardly by the piston in contact with a shoulder of the piston.

45 A further object is to so construct the drive and associated parts that the power hammer may be easily assembled to or disassembled from a flexible shaft for driving the same.

50 While the prior art discloses a great many air driven power hammers and some electrically driven power hammers, it has been found that these power hammers contain many objectionable features. The air hammers in commercial use at the present time are highly inefficient in view of the fact that air driven mechanisms of all types are known to have an efficiency of not over 15%. The electrically operated power hammers are ordinarily constructed with a motor

5 built into a housing adjacent the handle of the hammer, thereby causing additional expense for a motor housing and associated parts and also providing a device that is clumsy and bulky to handle and one which soon tires the average worker. Furthermore, it is obvious that due to the terrific pounding which the motor is subjected to by reason of the action of the chipper, hammer or other work tool, the motor will 10 quickly wear out or become broken. All of these objectionable features are eliminated in the simple, light and compact power hammer which I have devised.

Other objects and advantages will be more 15 easily understood from the following description, wherein reference is had to the accompanying five sheets of drawings, upon which

20 Fig. 1 is a side elevational view of my improved power hammer showing a work tool attached thereto in a driving relation;

Fig. 2 is a front elevational view of the manner 25 in which the flexible drive for the same extends from the side thereof;

Fig. 3 is a vertical sectional view through the cylinder housing and associated parts;

Fig. 4 is a bottom fragmentary view taken generally on the lines 4—4 of Fig. 3 showing the adjustment for the operating lever recoil spring;

Fig. 5 is a vertical sectional view taken generally on the lines 5—5 of Fig. 1 and showing the 30 drive connection between the flexible shaft and the operating lever;

Fig. 6 is a plan sectional view through the housing, the operating lever and associated parts, taken generally on the line 6—6 of Fig. 1;

Fig. 7 is an elevational view of the reciprocating piston;

Fig. 8 is an elevational view of the forked operating lever, and

Fig. 9 is a side elevational view of the removable cylinder in which the operating piston operates.

45 In the embodiment of my invention which I have chosen to illustrate, I provide generally the handle 10 connected between the cylinder housing 12 and the mechanism housing 14.

To the side of the mechanism housing 14 I attach the housing 16 to which the housing 18 for the flexible shaft may be connected. The holder 20 provided with the right angle handle 50 22 is placed in the bottom of the cylinder housing 12 and may have connected thereto a work tool such as the chipper C shown in Fig. 1.

55 Referring now to Fig. 3, it can be seen that the handle member 10 may be in the form of a

- tubular member that has its ends flattened. One end of the member 10 is connected by means of the bolt 24 to an upright flange 26 on the housing 14 and the other end is bent at right angles 5 and has a ledge portion 28 that is fastened on the top of the cylinder cap 30 by means of a bolt member 32'. The housing 12 and the housing 14 which are formed integral, may have a pair of separated chambers 32 and 34. The 10 chamber 32 may be formed with vertical cylindrical walls and a flat upper edge 36. The cylinder 33 within which the work piston operates is adapted to be closely fitted in the bore 31 in the cylinder housing 12, having its upper edge 38 15 flush with the top of the cylinder housing 12 and having a shoulder 40 adapted to engage against the lower edge 42 of the housing 12. The cylinder may be formed with a vertical bore 44 terminating adjacent its upper end in an enlarged 20 screw-threaded opening 46. The cylinder cap 30 is formed with a downwardly depending threaded plug portion 48 that is adapted to screw-threadedly engage the opening 46. The cap is further provided with a cylindrical flange 50 25 rounding the plug 48 so that when the cap is screwed into position within the cylinder 33, the shoulder 50 is adapted to rest against the upper edges 36 and 38 of the housing 12 and the cylinder 33. The cylinder 33 may have a tapered bore 52 extending inwardly and connecting with a reduced bore 54 adjacent the lower end of the same. The bore 54 may extend downwardly for a distance, terminating in an inwardly directed and horizontal wall 56 where it connects 30 with a further reduced bore 58. The cylinder is also provided with a generally rectangularly shaped opening 60 adjacent one side of the same to permit the introduction of an operating lever as will presently be apparent.
- 40 I provide a tool retainer bushing 62 adapted to be fixedly held in the bore 58 at the lower end of the cylinder 33. I also provide a hammer head bumper 64 preferably made of a molded synthetic rubber compound positioned about the bushing 62 and generally upon the set 56 in the bore 54. With the construction as thus described and shown, the end 20a of the tool retainer 20 will extend upwardly a short distance above the bushing 62 and the bumper 64. The 45 reciprocating piston 66 may be formed with an upper cylindrical portion 68, a shank 69 and a lower cylindrical portion 70. The portion 68 is adapted to be guided in its reciprocal motion in the bore 44 of the cylinder 33 and may be provided with suitable piston rings 72 to provide a seal between these parts.
- The cylindrical portion 70 is adapted to reciprocate within the reduced bore 54 of the cylinder 33 and is in turn provided with a pair 50 of oil packing rings 74 which generally provide a seal between the piston head and the bore 54 and also serve to reciprocate the same. The upper portion 66 of the piston 70 may be formed with the vertical opening 76 and the raised stud portion 78 therein. A comparatively heavy compression spring 80 is adapted to be positioned in the opening 76 between the lower wall thereof and the lower wall of a socket 82 formed in the lower wall of the cylinder cap 30. I also provide a piston snubber block 84 positioned in a vertical opening 86 in the cylinder cap 30 between the head of the bolt 32' and the top of the stud 78.
- With the construction of the reciprocating 75 piston and the cylinder as thus far described, it

will be obvious that upon raising the piston 70 to the position shown in Fig. 3, the same will be adapted to be moved downwardly very quickly by the combined action of the compression spring 80 and the air that has been compressed within 5 the cylinder above the piston. By means of the piston rings 72 and the seal that is effected thereby, the air within the cylinder is thus compressed to a considerable degree with the result that the instant the force raising the 10 piston is released, the piston will be plunged downwardly against the top 20a of the tool holder 20 with considerable force.

The means for raising the piston to the operative position discussed will now be described. 15 The neck portion 69 of the piston 70 is formed with the cylindrical shoulder 88. This is adapted to be engaged by the upper cammed surface 90 of the fingers 92 at the end of the operating lever 94. The lever 94 has a hub portion 96 provided with a bore 98 through which a pivot pin 100 is positioned. The pivot pin 100 may be formed with a cylindrical head 102 adapted to be journalled in a socket 103 in the housing 14 and a reduced portion 104, adapted 20 to be journalled in a boss 105 extending inwardly from the cover portion 106 of the flexible drive housing 16. A nut member 108 secured to a threaded portion 110 on the pin 100 securely holds the pin in position in the housings mentioned. The lever 94 may be formed with spaced side walls 94a between which a roller 112 is adapted to be mounted upon a suitable pivot 114. In order to reduce friction to a minimum, a roller 112 has been provided with a ball bearing 35 mounting upon the pin 114. Means for reciprocating the lever 94 in an up and down direction are provided in the form of a cam 116. The cam 116 is formed with the rise track 118 and the drop track 120 which, as will be noted, 40 provides a gradual rising of the lever and an abrupt drop of the same. Thus, when the cam is rotated in the direction of the arrow as shown in Fig. 3, the lever 94 will raise the piston 70 to the position shown in the drawings, and as the 45 cam passes from the high point, the cam will not interfere with the sudden drop of the roller 112 or the drop of the piston 70. In this manner the effective blow struck by the piston will receive its entire momentum from the compression 50 spring 80 and the compression of the air in the chamber of the cylinder above the piston as previously explained.

In order to provide a shock absorber or snubber action for the lever 94, I provide the compression spring 122 positioned between a portion of the lever 94 and the top of a washer 123 secured on an adjusting bolt 124. The adjusting bolt 124 may be screw-threadedly mounted in a block 125 that has been cast integral with the housing 14. I provide a spring clip member 127 secured in position by one of the bolts 14a of the housing 14 that normally holds the head 128 of the adjusting screw 124. Thus, when it is desired to increase or decrease the tension on the spring 65 122, this action may be effected by turning the head 128 by means of a hexagonally headed wrench that is placed in the socket 129 in the screw head.

As previously mentioned, the flexible drive 70 housing 16 is secured to the side of the housing 14 and is formed with the cover plate portion 106 that engages about the periphery of the side opening 132 in the housing 14. These housings may be rigidly secured together by means of the 75

bolt members 14a which pass through suitable openings in both housings. In order to provide liquid proof seals, suitable gaskets are provided about the openings. Means for rotating the cam 5 116 may include the shaft 134 fixedly secured to the cam 116 and mounted in the flexible drive housing 16 between suitable needle bearings 136 adjacent both ends of the shaft. A suitable spacer 10 138 may be provided between the sets of bearings. The cam shaft 134 is formed with an axial opening 140 adapted to receive the tip 142 of a flexible drive shaft 144. The housing 146 may be connected in the end of the housing 14 in the well known manner, and the flexible drive shaft 15 144 may engage the splined driving tip 142a of the shaft 134 and in this way the flexible shaft is connected to the cam shaft to drive the same.

From the foregoing description, it will be apparent to those skilled in the art that a comparatively simple, yet highly efficient power hammer construction has been provided. It will also be obvious that by the simple expedient of removing the handle 10 and the cylinder cap 30 the cylinder and its associated parts may be 20 withdrawn for repair or replacement. By reason of the construction of the cam, it can be seen that the lever 94 is forced upwardly and then to effect the work stroke the cam, by reason of its shape is quickly gotten out of the way of the 25 descending roller 112, thus providing in this construction highly efficient means for a work hammer construction. By reason of the cushioning at the bottom of the piston stroke, it is 30 obvious that all of the parts will wear longer 35 because there is no harsh pounding as is found in many of the hammers at present in use. The cushioning of the lever in its descent is also a desirable feature which adds greatly to the life and satisfactory operation of applicant's construction.

While I have illustrated and described one embodiment of my invention, it will be obvious to those skilled in the art that changes and modifications may be made in the details shown, 45 and I do not wish to limit myself in any particular; rather what I desire to secure and protect by Letters Patent of the United States is:

1. A mechanically driven power hammer including in combination, a housing having a cylinder, a piston reciprocably mounted in said cylinder, a work engaging tool one end of which is removably extended into one end of the cylinder in a position to be engaged by one end of said piston, a compression spring disposed in 50 the cylinder between the other end thereof and the other end of the piston, and piston operating means including a lever extending transversely of the longitudinal axis of said piston, engaging the piston at one end, and pivoted to 55 the housing at its other end for swinging movement in the common plane of the lever and piston, a cam rotatably mounted in said housing intermediate the ends of the lever, on the opposite side of the lever from said compression 60 spring and adapted to move said lever against the compression of said spring, and a flexible shaft drive for said cam.

2. A mechanically driven power hammer as defined in claim 1, wherein the piston has a reduced waist region defined between spaced shoulders, and wherein the piston engaging end of the lever is in the form of a fork embracing said reduced waist region and engageable against said shoulders.

3. A mechanically driven power hammer in-

cluding in combination, a housing having a cylinder, a piston reciprocably mounted in said cylinder, a work engaging tool one end of which is removably extended into one end of the cylinder in a position to be engaged by one end of 5 said piston, a compression spring disposed in the cylinder between the other end thereof and the other end of the piston, and piston operating means including a lever extending transversely of the longitudinal axis of said piston, 10 engaging the piston at one end, and pivoted to the housing at its other end for swinging movement in the common plane of the lever and piston, a cam rotatably mounted in said housing intermediate the ends of the lever, on the 15 opposite side of the lever from said compression spring and adapted to move said lever so as to move said piston against the compression of said spring and compress the air between said piston and an end of the cylinder, and a flexible 20 shaft drive for said cam.

4. A mechanically driven power hammer including in combination, a housing having a cylinder, a piston reciprocably mounted in said cylinder, a work engaging tool one end of which is removably extended into one end of the cylinder in a position to be engaged by one end of 25 said piston, a compression spring disposed in the cylinder between the other end thereof and the other end of the piston, and piston operating 30 means including a lever extending transversely of the longitudinal axis of said piston, engaging the piston at one end, and pivoted to the housing at its other end for swinging movement in the common plane of the lever and 35 piston, a cam for moving the lever against the compression of said spring and a recoil spring for cushioning the lever on the working stroke of the piston, said cam and recoil spring being both disposed intermediate the ends of the lever 40 on the opposite side thereof from said compression spring, and a flexible shaft drive for said cam.

5. In a mechanical power hammer the combination of a housing having a vertical bore 45 through one side thereof, a removable cylinder mounted in said bore, said cylinder having a shoulder adjacent its lower end engaging the bottom of said housing and a cap secured thereto at its top and engaging the top of said housing whereby said cylinder is held in fixed position therein, a reciprocable piston mounted in said cylinder, a work tool adapted to be extended from the lower end of said cylinder, a compression spring in said cylinder positioned between 50 said cap and the upper end of said piston, a pivoted arm for raising said piston and a rotatable cam for operating said arm, said cam driven by means of a flexible drive shaft.

6. In a mechanical power hammer the combination of a housing having a vertical bore 60 through one side thereof, a removable cylinder mounted in said bore, said cylinder having a shoulder adjacent its lower end engaging the bottom of said housing and a cap secured thereto at its top and engaging the top of said housing whereby said cylinder is held in fixed position therein, a reciprocable piston mounted in said cylinder, a work tool adapted to be extended from the lower end of said cylinder, a compression 65 spring in said cylinder positioned between said cap and the upper end of said piston, a pivoted arm for raising said piston and a rotatable cam for operating said arm, a shaft for said cam extending at right angles from said hous- 70

- ing, a drive nut secured thereto, a flexible shaft having a tip engaging said drive nut and a remotely placed source of power for said shaft.
7. In a mechanical power hammer the combination of a housing, a removable cylinder mounted in said housing, a reciprocable piston mounted in said cylinder, a work tool adapted to be extended from one end of said cylinder, a cap in the other end of said cylinder, a compression spring in said cylinder positioned between said cap and the upper end of said piston, a flexible bumper member in said cylinder above said piston, a pivoted arm for raising said piston to compress said spring, a revolving cam for raising said arm, a bumper spring below said arm and means including a flexible drive shaft for operating said cam.
8. A mechanically driven power hammer including in combination, a housing having a cylinder, a piston reciprocably mounted in said cylinder, a work engaging tool one end of which is removably extended into one end of the cylinder in a position to be engaged by one end of said piston, a compression spring disposed in the cylinder between the other end thereof and the other end of the piston, and piston operating means including a lever extending transversely of the longitudinal axis of said piston, engaging the piston at one end, and pivoted to the housing at its other end for swinging movement in the common plane of the lever and piston, a cam rotatably mounted in said housing intermediate the ends of the lever, on the opposite side of the lever from said compression spring and adapted to move said lever against the compression of said spring, and resilient bumper means in the cylinder between the tool engaging end of the piston and the adjacent end of the cylinder, and a flexible shaft drive for said cam.
9. A power hammer comprising a housing, said housing having a vertical bore adjacent one side thereof, a cylinder mounted in said bore, said cylinder having a flange engaging the lower wall of said housing, a cap for said cylinder engaging the upper wall of said housing and thereby locking said cylinder in position in said housing, a piston in said cylinder, means for raising said piston comprising a lever mounted in said housing, a cam for operating said lever, a flexible drive connected to said cam and spring means positioned between said cap and the upper end of said piston for lowering said piston in a hammer thrust, said piston provided with piston rings whereby air is compressed upon the upward stroke of said piston.
10. A power hammer comprising a housing, said housing having a vertical bore adjacent one side thereof, a cylinder mounted in said bore, said cylinder having a flange engaging the lower wall of said housing, a cap screw-threadedly mounted in the upper end of said cylinder engaging the upper wall of said housing and thereby locking said cylinder in position in said housing, a piston in said cylinder comprising a lever mounted in said housing, a recoil spring below said lever, a cam in said housing for raising said lever, a drive shaft for said cam, a flexible drive connected thereto and compression spring means positioned between said cap and the upper end of said piston for lowering said piston in a hammer thrust, a resilient bumper positioned between the coils of said second spring, said piston provided with piston rings whereby air is compressed upon the upward stroke of said piston.
11. A power hammer comprising a housing, said housing having a vertical bore adjacent one side thereof, a cylinder mounted in said bore, said cylinder having a flange engaging the lower wall of said housing, a cap screw-threadedly mounted in the upper end of said cylinder engaging the upper wall of said housing and thereby locking said cylinder in position in said housing, a piston in said cylinder, means for raising said piston comprising a lever mounted in said housing, a recoil spring below said lever, means for adjusting the tension on said spring, a cam in said housing for raising said lever, a drive shaft for said cam, a flexible drive connected thereto and compression spring means positioned between said cap and the upper end of said piston for lowering said piston in a hammer thrust, a resilient bumper positioned between the coils of said second spring, said piston provided with piston rings whereby air is compressed upon the upward stroke of said piston.
12. In a mechanical power hammer the combination of a housing having a vertical bore through one side thereof, a removable cylinder mounted in said bore, said cylinder having a shoulder adjacent its lower end engaging the bottom of said housing and a cap secured thereto at its top and engaging the top of said housing whereby said cylinder is held in fixed position therein, a reciprocable piston mounted in said cylinder, a work tool adapted to be extended from the lower end of said cylinder, a compression spring in said cylinder positioned between said cap and the upper end of said piston, a rubber bumper on both sides of said piston for effecting a snubbing action to the movement of the piston, a pivoted arm for raising said piston and a rotatable cam for operating said arm, said cam driven by means of a flexible drive shaft.
13. A mechanically driven power hammer as defined in claim 4, including an adjusting element, extending into the housing from the exterior thereof, for adjusting the tension of said recoil spring.

ARTHUR WILLIAM MALL.

60
